(57) **CLAIM**

The ornamental design for a broadhead, as shown and described.

DESCRIPTION

FIG. 1 is a front perspective view of the broadhead;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

Features shown in broken lines do not form any part of the claimed design. Any broken lines immediately adjacent the solid-line portions of the design form the boundary of the design, with the broken lines forming no part of the claimed design.

1 Claim, 4 Drawing Sheets
